ALARM SELECTOR APPARATUS

Louis L. E. Chauveau, Paris, France

Application November 19, 1928, Serial No. 320,397
In France December 2, 1927

9 Claims. (Cl. 177—353)

It is well known that International Commissions have been considering the addition to the SOS distress signal of ships of another signal more particularly intended to actuate electromagnetic alarm selectors automatically thus insuring a "distress watch" in the absence of the radio operator on the vessel. This new signal consists in sending out during say one minute intervals a series of dashes of four seconds separated by intervals of one second.

The present invention relates to a selector device having as one of its objects the actuation of one or more electric bells or other alarm devices as soon as a series of three consecutive dashes of four seconds each and separated by intervals of one second have been accurately recorded by the assembly comprising the radio receiver and the alarm selector.

One embodiment of the basic idea of the invention will hereinafter be described by reference to the accompanying drawing, shown by way of example only, wherein

Figure 1 is a diagrammatic view of a selector, according to the present invention responsive to three four-second dashes, and

Figure 2 is a modified form of the apparatus.

The alarm selector comprises three principal parts, viz., (1) the dash controller; (2) the space controller; and (3) the recorder.

The dash controller is adapted to measure the length of the incoming dashes. It comprises (a) an equilibrated balance of the spiral type 49 adapted to be liberated by means of an electromagnet 54. The natural period of the balance 49 is one second; in other words, it goes through two half-vibrations in each second. This balance controls sets of contacts disposed in such a way that an electric impulse is sent into the line 51 at the end of each oscillation of the balance; (b) a series of successively closed electromagnets 26, 28, 30 and 32 combined with auxiliary electromagnets 27, 29, 31 and 33 adapted to be successively energized as impulses are sent out into the line 51, so that 26 operates at the end of the first second, 28 at the end of the second second, and so on.

The dash controller allows for the measuring, in seconds, of the length of the incoming dashes. Its functions are: to prepare at the first second the circuit of an electromagnet adapted to restore the system to zero position, feed a line 47 actuating the recorder with current at the end of the second second, and prepare at the very same second a zero-restoring electromagnet,

while at the fifth second it serves to render the zero-restoring electromagnet operative.

The result is that if the dash lasts longer than a second and less than three seconds, the apparatus is restored to normal. If the dash lasts three seconds, the recorder advances one step forward. If the dash lasts five seconds, the apparatus is restored to normal.

The space controller is adapted to actuate the zero-restoring electromagnet if the space between two incoming signals attains two seconds. The same comprises: (a) a spiral-type equilibrated balance 50 adapted to be liberated by an electromagnet 57. The natural period of balance 50 is also one second, and it actuates and controls sets of contacts in order that an electric impulse may be sent into a line 66 at the end of each oscillation of the balance; (b) two electromagnets 60 and 59 disposed so that 60 functions at the end of the first second and that an impulse is sent into the line 66 at the termination of the second second.

The result is that if the space attains two seconds, the zero-restoring electromagnet 35 is operated and that the apparatus is restored to normal.

The recorder consists of a series of successively closing electromagnets 42, 43 and 44 combined with auxiliary electromagnets 41, 40 and 39 in order to be energized successively each time that current is sent into line 47, in other words, each time that a dash attains a length of three seconds.

The last relay 39 closes the circuit of a bell 65 which is thus set to operate immediately after the third dash has come in correctly. The circuits of the recorder relays 42, 43 and 44 and 41, 40 and 39 may be broken by the zero-restoring electromagnet 35.

It will be seen from this arrangement that if three correct dashes separated by two correct intervals are received, the bell 65 becomes operative, and that, if an incorrect dash or space should be received, the apparatus is restored to normal. The arrangement of the system is such that every dash having a length equal to or greater than three seconds, but less than five seconds is considered as accurate, and that each interval having a length less than two seconds is considered as correct. Tolerance in this regard is necessary so as to permit the radio operator on the distressed vessel to send out an alarm or call signal more or less suited to actuate the selectors seeing that in most cases he has only a simple watch available for checking.

Referring to the drawing, operation of the assembly is as follows:

- Supposing that a four-second dash has been received, then the relay device 56, which is the output of a wireless receiver, closes the switch 55, the manipulating relay 54 is energized and thus attracts its keeper 1. The end of the arm of the armature 1 is forked and the shaft 3 passes between the forked members as indicated in the drawing. When the magnetic winding 54 is demagnetized the armature 1 moves into the position indicated in the drawing under the action of the spring 53, the rod 3 is held unmoving, contact 6 is closed, and contact 5 rests upon the lower leaf member. When winding 54 is energized the armature 1 is drawn down, the forked member at the end is raised and allows the movable member of contact 5 to make contact with the upper leaf. This contact member remains closed as long as winding 54 is energized. The keeper 1 liberates shoulder 2 of rod 3 which holds the spring of the balance wheel 49 in tension with the result that the balance wheel is thus released and starts to swing freely. The rod 3 being released by the forked member swings up and down as the member 49 oscillates. This motion of the rod member 3 periodically closes 6.

The arm of the keeper 1 at the end of its stroke closes the upper contact of switch device 5, with the result that all points marked +a become of positive polarity, including contact 6. The latter however has been opened because the balance has started to oscillate. The dash controller assembly is now prepared and ready to measure the first dash.

During the first half of the second (1/2 oscillation of 49), rods 3 and 4 ascend, while during the second half of the second, rod 3 descends and closes contact 6. The result of this is that an impulse is sent through the line 51. These movements are reproduced each second and at the end of each of them an impulse is sent into the line 51.

At the first impulse, 26 is energized by way of line 51 and contact 7 now closed. Relay 26 closes its guard contact 8, and this completes a circuit through a (at 8), 8, 27, 7, 6, a (at 5) back to a (at 8). During the impulse, however, 27 will remain inoperative because it is short-circuited by the rest contact (back contact) 7, working contact 6 and contact 5 in the upper position a (at 5) and a (at 8). However, as soon as the impulse stops, contact 6 is open, 27 no longer is short-circuited, it is energized through a (at 5), a (at 8), 8, 27, to 26 and causes connection of line 51 with line 52 by way of its contact 9, while it becomes isolated or severed from the said line 51 by its contact 7.

However, it will be seen from the last traced circuit that 26 will remain energized so that 8 will remain closed even though contact 7 is broken.

It will thus be seen that 26 operates at the end of the first second when an impulse is passed, and that 27 becomes operative immediately after this impulse.

Line 51 is then united by way of contact 9 and line 52 to the inlet or input end of 28. The latter therefore operates at the end of the second second at the time the second impulse is passed. As the arrangement of 28, 29 is the same as that of 26, 27, the relay 29 will become operative immediately after the second impulse and cause connection of line 51 with group 30, relay 31 by way of its contact 10.

At the end of the third second, at the time of

sending out the third impulse, relay 30 will operate; after this impulse 31 is energized and causes connection of line 51 over to the group 32, 33.

At the end of the fourth second, 32 operates 80 at the instant of the fourth impulse, and 33 is energized immediately after this impulse.

It will be thus seen that the electromagnets 26, 28, 30 and 32 are successively closed in proportion as impulses are sent into the line 51, that 85 is to say, at the end of each second.

Since it has been supposed that a four-second dash is received, at the end of the third second relay 30 when energized has caused current to flow into the line 47. The latter controls the 90 group of recorder electromagnets 42-43 and 41-39 the electrical operation of which is exactly the same as that described for the set of electromagnets 26-32 and 27-33, etc.

Consequently, as soon as 30 functions, electromagnet 42 is energized through the plus terminal of the right hand contact operated upon by relay 30, line 47, contact 13, relay 42 to minus via contact 36, and is so kept by its contact 12, while 41 remains short-circuited by its contact 13 and contact 14 of 30.

After the four-second dash, switch 55 is opened, electromagnet 54 is no longer energized, keeper 1 is released whereupon being drawn downwards by the spring 53, with the result that the balance 105 wheel 49 is locked. Now, at the same time, contact 5 leaves its upper contact, points +a are no longer fed, and the relays 26 to 32 and 27 to 33 being deenergized assume their original states.

At this instant the contact 14 of 30 is open, 110 the relay 41 is no longer short-circuited, it operates and switches the line 47 by way of contact 11 onto the group 43-40 through contact 46. It will thus be seen that the reception of the first dash of four seconds has resulted in the 115 energization of the recorder group 42-41.

Supposing, then, that a correct series of dashes of four seconds is received, then upon the second dash the group of dash relays 26-32 and 27-33 will become again operative. When 30 is energized a current will be caused to flow in line 47 and the electromagnet 43 will be energized.

After the second dash, the group of dash relays will come to rest, but the recorder relays 42, 43, 41 and 40 will be energized. Upon the third dash, 125 the dash relays are operated again, the line 47 will operate.

After the third dash, the group of dash relays comes to rest, but all of the recording relays will then be energized. It will be noted in particular 130 that the relay 39 is then excited, that its contact 16 is closed, and that the bell 65 is caused to ring. Now, the said relay 39 has a guard (holding) coil 38 fed by way of contact 15. The result is that, whatever signals may follow, the alarm 135 bell 65 will continue to ring until it is stopped. It will be understood that any desired number of alarms 65 could be connected in shunt to the same circuit for giving the alarm in different places.

Supposing then, that one of the number of incoming dashes has lasted for five seconds. After the fourth second, the relay 33 will operate, and its contact 17 has connected line 51 with line 34. 145

The result is that at the termination of the fifth second, when impulsed, the relay 35 will become operative and break the common return of the recording relays through contact 36. This group is thus set at rest, indeed, another complete 150

correct signal will be required in order to operate the bell.

In case the dash lasts longer than five seconds, 35 will operate at each second unless finally the balance 49 is stopped by its damping means.

Assuming now that any one of the dashes has had a duration longer than one second but less than three seconds. At the end of the first second 26 has become energized, contact 18 is closed 10 and this feeds the coil 20 of relay 48, the latter closes its contact 19 whereby the line 64 is connected with line 34; at the end of the unduly short dash, 54 becomes de-energized, contact 5 is moved over to its lower contact and a current is caused 15 to flow in line 64 and consequently line 34, the zero restoring relay 38 operates and renders the recorder group inoperative.

But if, on the contrary, the dash has been correct, then, upon operation of relay 30 the coil 20 21 of relay 48 would have been energized. The coils 20 and 21 of 48 are equal but opposite, their action is neutralized, and as a consequence 19 would have been opened and the flow of current in line 64 would have been ineffective.

It will be noted that relay 48 has a slight time-lag ring 67, in order that 48 may remain energized a short instant after 26 has come to rest in order that the zero impulse by line 64 may become effective. It will thus be seen that every dash 25 longer than a second and less than three seconds causes the system to be restored to zero.

Every dash having a length less than one second is unable to produce an action upon the system. This is an advantage because the apparatus is thus made more flexible and cannot be influenced in any way by Morse signals of the usual manual rate. However, if for reasons of service it should turn out to be necessary to cause restoration to zero for dashes less than one second, 40 all that would then be required is to feed the coil 20 directly by way of the upper contact *a* of contact 5 without passing by way of contact 18 of 26. Under these conditions, 48 would be energized as soon as an action of relay 49 occurs, and 45 a dash, no matter how short, would cause restoration to zero.

Check-up on the silence periods or spaces is effected in the following manner: As long as the signal has not been started, it is unnecessary to 50 measure these periods, and it is for this reason that the circuit of relay 57 passes by way of line 37 and contact 22 of relay 42. Under these conditions, immediately after reception of the first correct dash, contact 5 is caused to move to its rest or back contact, and 57 is energized, and its controls an equilibrated balance wheel 50 of the 55 spring type being in all regards similar to 49. The result is that a current is caused to flow in line 66 by way of contacts 23 and 24 at the end of each second of silence. At the end of the first 60 second, the relay 60 is energized, and immediately thereafter the relay 59 is energized and connects line 66 by way of its contact 25 with the line 34. The result is that if the silence period or space 65 between any two dashes lasts two seconds the zero relay is operated and causes the recorder to re-store.

It will thus be noted that the silence period or space between signals is regarded as correct as long as it does not last two seconds or over. In order to facilitate understanding of the function of the balances and of the contacts of the same, balance wheel 49 is shown locked, which is the correct position, whereas balance 50 is shown free although the contact 22 of 42 is open.

Another embodiment of the same selector given by way of example is shown in Figure 2 and claimed in my Patent 1,934,912, dated Nov. 14, 1933. The assembly of balances and relays 26, 32, 27, 33, 60 and 59 is replaced by a mechanical 80 device constructed in the following manner.

A wheel 81 is rotated in a continuous manner at the rate of one revolution per second, either constantly by means of a motor fed from a source or a clockwork, or else only at the time when signals are coming in. In this latter case the movement of the wheel 81 is controlled either by the manipulating relay 71 or by the spacer relay 87 or better by a relay in series with a wire common to the circuits of these two electromagnets. 90

As the wheel 81 is assumed to have a constant rate of speed of 1 revolution per second, the relay 71 playing the part of 54 is energized upon the reception of dashes, and causes meshing between the wheel 77 and the drive wheel 81. The wheel 77 will then revolve at the rate of 1 revolution each 10 seconds or else a half turn in five seconds. Then, assuming that the beginning of motion of wheel 77 is fixed by stop 91, the shoulder 74 of this wheel will close the contact 70 when the 100 incoming dash has lasted for a second, contact 90 when the incoming dash has lasted three seconds, and 78 when the incoming dash has lasted five seconds.

Contacts 70, 90 and 78 play the same part as 105 the contacts 18, 14 and 17, Figure 1. Consequently the action of the assembly of 71 and wheel 77 is exactly the same as that of assembly 54, 49, 26, 28, 30 and 32 and 27, 29, 31, 33 in Figure 1.

When the incoming dash is finished, electromagnet 71 is no longer excited, and the wheel 77 is disengaged with wheel 81 by the spring 73, the said wheel 77 is restored to its position of rest by action of spring 75.

During the return movement of wheel 77, closure of contacts 90 and 70 is ineffective because at this instant the contact 72 no longer is on its upper contact.

Wheel 77 is made integral with wheel 81 by means of a friction device so that, if the dash 115 lasts longer than 5 seconds, wheel 77 does not continue rotating because it is arrested by its stop 76 coming then to bear upon the lower edge of support 80.

Of course, if such a system is to operate conveniently, it is necessary that the contacts 70, 90 and 78 should keep a constant position with relation to the spindle of wheel 77. For this purpose, they are supported by projection or lug 125 of support 80 not shown in the drawing. 130

The relay 87 operates like the relay 57 in Figure 1. It is then meshed or engaged on drive wheel 81 with a wheel 83 revolving one turn each two seconds. The beginning of the movement of wheel 83 is fixed by the stop 93 supported upon support 92. Hence, wheel 83 is coupled with wheel 81 during the periods of silence or spaces. It makes a half turn each two seconds, and the result is that if a space lasts two seconds the contact 86 is closed by finger 82, with the consequence that the zero electromagnet is rendered 140 operative.

The wheel 83 is also in frictional engagement with wheel 81 so that 83 does not continue to revolve in the presence of a space lasting over two 145 seconds, and after such period it is restored to its starting point by the spiral 84.

The relay circuit 87 is also connected by way of contact 22 of 42 in order that the space elec- 150

tromagnet 57 may be isolated as long as no dash has been recorded.

It follows from what precedes that a selector as here described allows of setting into action a bell whenever a signal consisting of three consecutive dashes conveniently spaced apart by suitable intervals of time is coming in.

What is regarded as convenient are dashes of a duration from three to five seconds, and spaces 10 of a duration lasting less than two seconds. The apparatus is restored to zero every time that a dash over one second and less than three seconds is received. Still, it could be modified in such a way that it will be set at rest every time that a 15 dash lasting less than three seconds is received.

The apparatus is restored to zero every time that a dash over five seconds or that a space over two seconds is recorded.

The figures for the length of the dashes and 20 the spaces hereinbefore given are merely by way of example, for they can be changed according to the signal to be received, and such an alteration is associated merely with a change in the period of the balances or of the electro-mechanical system of Figure 2. Also the number of elements of the recorded group could be changed, for 25 instance, with a view to receive signals comprising more than or less than three consecutive dashes.

Having thus described my invention, what I 30 desire to protect by Letters Patent is as follows:

1. In a call selector system, means responsive to received signals, a time interval measuring device operatively associated therewith only during the duration of the impulse effecting a periodic 35 alternating movement and closing an electric circuit once per period, a set of relay devices electrically associated with said circuit and interconnected to be successively and periodically operable in accordance with the measured time 40 intervals, a second set of relay devices inter-connected to be successively and periodically operated and means in said first mentioned relay devices operable upon the operation of a predetermined number thereof for operating one of said 45 second set of relays and means operable upon the operation of a predetermined number of said second set of relays for setting into operation a calling device, a zero restoring device associated with said circuit for discontinuing when energized 50 the excitation of the said second set of relays to render said calling device inoperative and means associated with the last of said first mentioned set of relays for rendering said zero restoring mechanism operable when the received signal is 55 of too great a length, a second time interval measuring device, means for rendering this device operative, the circuit of these means being associated with a device responsive to the signal during the duration of the dash and on the other 60 hand being associated with the first relay of the second set beforementioned, a circuit periodically closed by the second device for measuring the length of time, and means controlled thereby for rendering said zero restoring mechanism operable 65 when the received signal is improperly spaced and means including said first mentioned means in order to render operative the zero restoring system when the received signal is of too short duration.
2. In a call selector, means responsive to received signals, a time interval measuring device operatively associated therewith only during the duration of the impulse and effecting a periodic alternating movement and closing an electric circuit once per period, a plurality of relay devices 70

electrically associated with said circuit and interconnected to be successively and periodically operated in accordance with said measured intervals, a second set of relay devices and means controlled by said first mentioned relay devices and operative upon the operation of a predetermined number thereof for rendering said second set of relay devices selectively and successively operative and means controlled by the operation of a certain predetermined relay device of said second set for operating a calling device, and a second time interval measuring device, means in circuit with said first time interval measuring device and responsive to a non-operative condition of said first time interval measuring device for rendering said second time interval measuring device operative, said second time interval measuring device being arranged when operative to render said calling device inoperative upon the receipt of an improper signal.

3. In a call selector, means responsive to received signals, a time measuring device associated with said means, an electric circuit, means interposed between said device and said circuit to periodically make and break the latter, a plurality 100 of relay devices operatively associated with said circuit and arranged to be successively operated by energy therein, a second set of relay devices operatively associated with said first mentioned relay devices and means operative upon the operation of a predetermined number of said first mentioned relay devices for rendering said second relay devices operative, a calling device associated therewith, and means controlled by the operation of a certain predetermined relay of said 110 second set for operating said calling device.

4. In a signal selective apparatus responsive to a predetermined number of dashes and spaces of predetermined time duration in combination, a signal responsive device, a recorder device comprising a series of normally opened relay circuits each of said relay circuits having means for closing the circuit of the relay immediately following at the end of each signal impulse of correct time duration, a utilizing circuit and means upon the 120 operation of the last of said relays for rendering said utilizing circuit operative, a dash controller comprising a second series of normally opened relay circuits each thereof having means for closing the circuit of the relay immediately following 125 at predetermined intervals of time, an oscillating escapement device for determining said intervals of time, the last of said last named series of relays having means for transmitting an impulse to said recorder if the duration of the received signal impulse is correct and rendering the whole system 130 inoperative if incorrect, and an interval controller comprising means for measuring the length of the interval between signal impulses and means when any interval between signal impulses is incorrect for returning the entire system to its original condition.

5. In a selective apparatus responsive to a certain predetermined series of signals, means for measuring the length of a particular signal impulse comprising a signal responsive device, an oscillating escapement mechanism arranged to be set into motion thereby upon the receipt of a signal, an electric circuit, means including said oscillating mechanism for periodically sending a 145 current impulse through said circuit, a series of relay devices operatively associated with said circuit, means for successively operating said relay devices in accordance with said impulses, a recorder device and means associated with the last 150

- of said relay devices for rendering said recorder device operative upon said last named relay device being operated.
6. In a selective apparatus responsive to a certain predetermined series of signals, means for measuring the length of a particular signal impulse comprising a signal responsive device, an oscillating escapement mechanism arranged to be set into motion thereby upon the receipt of the signal, an electric circuit, means including said oscillating mechanism for periodically sending a current impulse through said circuit during the duration of a particular signal impulse, a series of relay devices operatively associated with said circuit and means for successively operating one of said relay devices each time a current impulse is sent through said circuit, a second series of relay devices operatively associated with said first named series of relay devices and means for successively operating one of said second named series of relay devices each time that all of said first named series of relay devices are successively operated.
7. In a selective apparatus responsive to a certain predetermined series of signals, means for measuring the length of a particular signal impulse comprising a signal responsive device, an oscillating escapement mechanism arranged to be set into motion thereby upon the receipt of the signal, an electric circuit, means including said oscillating mechanism for periodically sending a current impulse through said circuit during the duration of a particular signal impulse, a series of relay devices operatively associated with said circuit and means for successively operating one of said relay devices each time a current impulse is sent through said circuit, a second series of relay devices operatively associated with said first named series of relay devices, means for successively operating one of said second named series of relay devices each time that all of said first named series of relay devices are successively operated.
8. In a selective apparatus, signal responsive means, an oscillating escapement device arranged to be rendered operative thereby upon receipt of a signal impulse, a series of normally disconnected relay devices each thereof having means for connecting the relay device immediately following in series therewith, means upon receipt of a signal impulse for rendering the first of said relay devices operative, means upon each successive swing of said oscillating escapement device during the receipt of said same signal impulse for successively connecting said relays in series and means for recording the number of signal impulses comprising a series of normally disconnected relay devices each thereof having means for connecting the relay device immediately following in series therewith and means upon the connection of the last of said relays for rendering operative a calling device.
9. In a call selector having a calling device arranged to function upon the receipt of a desired combination of signal impulses, circuit means for operating said device, and a signal responsive controlling element for controlling said means, the combination of a periodic balance escapement mechanism responsive to said element for periodically making and breaking the circuit means, and an additional periodic balance escapement mechanism in circuit with said means and arranged to be operated upon each deenergization of said element for restoring the selector to normal on the reception of an undesired signal.
